CLAIM

The ornamental design for a colander or the like, as shown and described.

DESCRIPTION

FIG. 1 is a top perspective view of a colander or the like showing our new design;
FIG. 2 is a top plan view thereof;
FIG. 3 is a bottom plan view thereof;
FIG. 4 is a left side elevational view thereof, the opposite side being identical thereto;
FIG. 5 is a rear elevational view thereof; and,
FIG. 6 is a front elevational view thereof.
